UNITED STATES PATENT OFFICE.

WILLIAM J. YOUNG, OF MINETTO, NEW YORK.

SAFETY-VALVE FOR PNEUMATIC TIRES.

1,258,079.

Specification of Letters Patent.

Patented Mar. 5, 1918.

Application filed February 19, 1914. Serial No. 319,611.

To all whom it may concern:

Be it known that I, WILLIAM J. YOUNG, a citizen of the United States, residing at Minetto, county of Oswego, State of New York, have invented an Improvement in Safety-Valves for Pneumatic Tires, of which the following description, in connection with the accompanying drawing, is a specification, like characters on the drawing 10 representing like parts.

This invention relates to safety valves for pneumatic tires which are designed to relieve the pressure within the tire when the latter exceeds a predetermined amount, 15 and it has for its object to provide a novel safety valve of this type, all as will be more fully hereinafter described and then pointed out in the appended claim.

The drawings show a sectional view illustrating a selected embodiment of my invention from which the principle thereof will be readily seen.

1 designates the ordinary valve stem of a pneumatic tire having the usual valve 2 25 therein provided with a valve stem 3, said valve being normally seated by the spring 4. These are the parts which are of common construction and form no part of my present invention.

20 In accordance with my invention I provide a member 5 which is adapted to be screwed to the screw-threaded end 6 of the valve stem 1, said member having at its inner end a guiding head 7 which fits over the 25 valve stem and which coöperates with the screw-threaded portion to hold the member 5 firmly in place. This member 5 is provided with an outer chamber 8 which communicates with the bore of the valve stem 1 30 through a passageway 9 and this passageway is normally closed by a balanced safety valve 10 which is held against a seat 11 by means of a spring 12. The spring is shown as backed against an adjustable plate 13 35 that is screw-threaded into the chamber 8 and by means of which the tension of the spring may be controlled. The outer end of the casing 5 is closed by a removable cap 14 which is provided with a stem 15 constituting an auxiliary valve chamber. Within this stem a valve seat member 16 is secured with which coöperates a safety valve 17 that is held to its seat by a spring 18. This spring 18 is backed against a cap 19 that 40 is adjustably secured to the stem 15, said cap being provided with the port 20. The 45

plate 13 is also provided with a port 21 for the escape of air.

The safety valve 10 is provided with a central aperture 22 having a valve seat 23 60 at its inner end, which valve seat is normally closed by an inwardly-opening check valve 24 that is held to its seat by a spring 25 arranged to engage a collar 26 on the end of the stem 27 of said valve 24. This valve 65 24 is also provided with a projection 28 of such a length that when the casing 5 is in proper position and the safety valve 10 is closed, this projection will engage the end of the stem 3 of the usual valve 2 and open 70 said valve away from its seat. Therefore, when my attachment is applied to a valve stem, the valve 2 with which the valve stem 1 is ordinarily supplied is open. The air in the tire, however, is prevented from escaping 75 by means of the valves 24 and 10, the valve 24 being held to its seat by air pressure and the spring 27, while the valve 10 which is an outwardly-opening valve is held to its seat by the spring 12. This spring 12 80 will have sufficient strength to hold the valve 10 seated against the ordinary pressure in the tire.

If, however, the pressure in the tire increases either permanently or momentarily 85 beyond the safety point by reason of the air in the tire becoming heated or because of the wheel running over obstructions, such increased pressure will open the valve 10 and allow a certain amount of air to pass 90 into the chamber 8. This chamber 8 may be made of any suitable size and if the amount of air which thus escapes into the chamber 8 is sufficient to relieve the excessive pressure in the tire, then the valve 10 will automatically seat itself again. If, however, the amount of air which escapes from the tire is greater than that required to fill the chamber 8, then the valve 17 will open, allowing the surplus air to escape through the 95 aperture 20. In either event, when the pressure in the tire has been restored to its normal, the valves 10 and 17 are closed automatically by their springs. The strength or tension of the springs 12 and 18 can be adjusted so that the safety valves will open 100 when any predetermined pressure is reached in the pneumatic tire, and the presence of these valves operates to prevent blow-outs from occurring.

The chamber 8 is in the nature of a storage chamber as it receives and stores up a

105

110

certain volume of air when any air escapes from the tire through the valve 10. After the pressure in the tire has been relieved by the escape of air into the chamber 8, the 5 pressure in said chamber will be substantially equal to that of the increased pressure in the tire, and this pressure will remain in the chamber 8 so long as the pressure in the tire does not decrease materially 10 below its normal amount. If, however, the tire pressure does decrease, then the greater pressure in the chamber 8 will open the valve 24, thus allowing some of the air in the chamber 8 to pass back into the tire 15 again.

It will be noted that the valve 10 is formed with the flange 31 by means of which the valve is practically balanced, thus making it more sensitive.

20 Having described my invention, what I claim as new and desire to secure by Letters Patent is:—

In a device of the class described, the combination with the valve stem of a pneumatic tire, of a casing secured thereto and provided with a chamber, said casing having an opening forming a communication between said chamber and the air passage of

said valve stem, the outer end of said opening constituting a valve seat, an outwardly-opening valve engaging said seat and having an extension which is received in said opening, said valve having an axial passage therethrough and the lower end of said extension constituting a valve seat, an inwardly-opening check valve carried by the outwardly-opening check valve and normally engaging the last-named valve seat, an apertured plate adjustably mounted in said chamber, a spring confined between said plate and said outwardly-opening check valve for yieldingly holding said valve to its seat, a cap detachably secured to the outer end of the chamber and provided with a neck, an outwardly-opening valve in the neck of the cap, an apertured cap screw-threaded to the neck of the first-named cap, and a spring confined between said second cap and said second outwardly-opening valve.

30 In testimony whereof, I have signed my name to this specification, in the presence of 35 two subscribing witnesses.

50 WILLIAM J. YOUNG.
